UNITED STATES PATENT OFFICE

148,650

DESIGN FOR A COMBINED CIGARETTE
LIGHTER AND CASE

Robert W. Snodgrass, Mount Morris, Mich.

Application April 25, 1946, Serial No. 128,955

Term of patent 14 years

(Cl. D85—2)

To all whom it may concern:

Be it known that I, Robert W. Snodgrass, a citizen of the United States, residing at Mount Morris, county of Genesee, State of Michigan, have invented a new, original, and ornamental Design for a Combined Cigarette Lighter and Case, of which the following is a specification, reference being had to the accompanying drawings, forming a part thereof.

Figure 1 is a perspective view of a combined cigarette lighter and case embodying my new design;

I claim:

The ornamental design for a combined cigarette lighter and case, substantially as shown.

ROBERT W. SNODGRASS.
